UNITED STATES PATENT OFFICE.

HARRY F. BUSHONG, OF KALAMAZOO, MICHIGAN, ASSIGNOR, BY MESNE ASSIGNMENTS, TO KALAMAZOO LOOSE LEAF BINDER COMPANY, A CORPORATION.

TEMPORARY BINDER OR LOOSE-SHEET HOLDER.

No. 851,276.

Specification of Letters Patent.

Patented April 23, 1907.

Application filed August 5, 1904. Serial No. 219,624.

To all whom it may concern:

Be it known that I, HARRY F. BUSHONG, a citizen of the United States, residing at the city of Kalamazoo, county of Kalamazoo, State of Michigan, have invented certain new and useful Improvements in Temporary Binders or Loose-Sheet Holders, of which the following is a specification.

This invention relates to improvements in temporary binders or loose sheet holders.

The objects of this invention are: First, to provide an improved temporary binder or loose sheet holder adapted to securely retain any number of sheets or leaves, from one to its maximum capacity. Second, to provide an improved temporary binder or loose sheet holder in which any particular sheet or leaf may be quickly released or removed, or a new sheet or leaf inserted without disturbing the other sheets or leaves. Third, to provide an improved temporary binder or loose sheet holder which is adapted to open flat and to hold the sheets or leaves so that they lie flat, or substantially flat, when the book is opened for use. Fourth, to provide an improved temporary binder or loose sheet holder in which the securing devices are so arranged that the strain thereon and upon the leaves in using the book is reduced to a minimum. Fifth, to provide an improved temporary binder or loose sheet holder in which the adjustment for the maximum or minimum number of leaves or for any intermediate number of leaves does not affect its finished and complete appearance. Sixth, to provide an improved temporary binder or loose sheet holder in which the adjustment of the back strip or piece is controlled by the adjustment of the clamping devices for the leaves or sheets. Seventh, to provide, in a temporary binder or loose sheet holder, an improved sheet clamping or retaining means.

Further objects and objects relating to structural details will definitely appear from the detailed description to follow.

I accomplish the objects of my invention by the devices and means described in the following specification.

The invention is clearly defined and pointed out in the claims.

A structure embodying the features of my invention is clearly illustrated in the accom-

panying drawings forming a part of this specification, in which—

Figure 1 is a plan view from the rear or outside of my improved temporary binder or loose sheet holder in its open position, the rear walls B' of the cover being removed and portions being broken away to show the arrangement of the parts. Fig. 2 is a longitudinal sectional view of my improved temporary binder or loose sheet holder in its closed position, taken on a line corresponding to line 2 2 of Fig. 1, the adjusting screw shaft D being shown in full lines. Fig. 3 is a detail longitudinal sectional view showing the arrangement of the sheet or leaf clamping means. Fig. 4 is a transverse sectional view taken on a line corresponding to line 4 4 of Fig. 2, showing further details of the clamping means for the sheets or leaves. Fig. 5 is an enlarged detail transverse sectional view taken on a line corresponding to line 5 5 of Fig. 2, showing the structural details of the covers. Fig. 6 is a longitudinal sectional view through one of the covers, showing the structural details thereof. Fig. 7 is a detail plan view of one of the sheets F, showing the key-hole shaped slot f therein.

In the drawings the sectional views are taken looking in the direction of the little arrows at the ends of the section lines, and similar letters of reference refer to similar parts throughout the several views.

Referring to the drawings, the covers are made up of rectangular frames consisting of side pieces A and end pieces A' A''. These frame pieces are preferably of wood. The inner walls B of the covers are made of sheet metal and are provided with rearwardly and inwardly turned flanges b' at each side, which embrace the side pieces A of the frame. The flanges of the walls are provided with projecting hinge pieces b at their inner ends. (See Fig. 6.) Finishing strips B'', preferably of wood, are secured to the outer faces of these flanges b'. The outer walls B' of the covers are secured upon the flanges b'. I am thus enabled to secure covers having a chamber therein, which are light and strong and of moderate thickness.

A pair of clamping bars C are pivotally secured to the hinge pieces b of the covers by the journals c. These clamping bars are pref-

erably flat on their inner or clamping faces and are preferably rounded on their rear or outer faces so that they may rock on their journals without engaging the inner edges of the covers. (See Fig. 2 and 3.) The clamping bars 5 C are provided with pairs of transverse perforations c' therethrough to receive the binding thongs or cords D'' which are arranged therethrough. These perforations or openings c' terminate in transverse slot-like cavities in the rear portions of the clamping bars to permit the same to rock freely on the binding cords. Thus arranged, the covers may 10 be opened without communicating the movement to the clamping bars. The binding cords or thongs D'' are secured to the bar D' transversely arranged in one of the covers. This bar is adjusted by means of the longitudinally arranged threaded shaft D which is 15 supported in suitable bearings d within the cover. This shaft is controlled by a suitable key, as d'. (See Fig. 1.) The binding cords D'' are preferably formed of a single piece which is looped around the block a. This 20 block a is preferably curved so that the binding cord is free to adjust itself over it, thereby maintaining an equal tension thereon and upon the clamping bars throughout their length. In loosening the clamping bars for 25 the insertion of leaves, the binding cord passes or slides back into the chamber in the cover, as indicated by the dotted lines in Fig. 1, which prevents any knotting or twisting thereof. However, the structure is quite 30 satisfactory with the binding cords independently and rigidly secured, instead of being connected and secured as illustrated in Fig. 1.

A back piece or strip E, adapted to telescope in the chambers in the covers, is provided. This back-piece is secured by tapes 35 e to the adjusting bar D' of the binding cords. (See Fig. 1.) The other end of the back-strip is secured by the tapes e' to the frame of the opposite cover. These tapes e e' are 40 preferably elastic, as this avoids the necessity for accurate adjustment of the parts in assembling.

With the parts thus connected, when the 45 clamping bars are adjusted, the back piece or strip is also adjusted so that it is automatically drawn out or telescoped within the covers, always presenting an attractive and finished appearance.

Any number of leaves or sheets, from one 50 to the maximum number, are securely retained by my improved loose sheet binder or holder.

My improved binder is adapted to open 55 flat, and at the same time the leaves or sheets 60 are so held that they lie flat—or practically so—when open for use, and the strain upon the binder and upon the leaves is reduced to a minimum. The leaves are clamped along their entire rear edge so that the danger of 65 their being torn is reduced to a minimum.

The device is very quickly adjusted for the insertion or removal of leaves, and the leaves are so held that there is no liability of their becoming detached from the clamping bars when loosened for the purpose of removing 70 or inserting leaves.

I have illustrated and described my improved temporary binder or loose sheet holder in the form preferred by me on account of its structural simplicity and the 75 economy with which the parts may be produced and assembled. I am, however, aware that it is capable of very great structural variation without departing from my invention. 80

Having thus described my invention, what I claim as new and desire to secure by Letters Patent, is:

1. The combination of the covers consisting of rectangular frames; inner walls of sheet 85 metal having rearwardly and inwardly turned flanges thereon embracing the sides of said frames; hinge projections on said flanges at their inner ends; rear walls for said covers secured to said flanges, thereby forming 90 chambers in the said covers; clamping bars having holes therethrough terminating in slot-like cavities at the rear, pivoted on said hinge projections; a curved block arranged in the chamber in one of said covers; a binding 95 cord looped about said block and arranged through said clamping bars, and projecting into the chamber in the opposite cover; a cross-bar to which the ends of said binding cord are secured; a threaded shaft supported 100 in suitable bearings for adjusting said bar; a back-strip adapted to telescope into the chambers in said covers; and elastic tapes for connecting one end of said back-strip to said cross-bar and the other end to the opposite 105 cover, all coacting for the purpose specified.

2. The combination of the covers consisting of rectangular frames; inner walls of sheet metal having rearwardly and inwardly turned flanges thereon embracing the sides of said frames; hinge projections on said flanges at their inner ends; rear walls for said covers secured to said flanges, thereby forming chambers in the said covers; clamping bars having holes therethrough terminating in 115 slot-like cavities at the rear, pivoted on said hinge projections; a curved block arranged in the chamber in one of said covers; a binding cord looped about said block and arranged through said clamping bars, and projecting 120 into the chambers in the opposite cover; a cross-bar to which the ends of said binding cord are secured; a threaded shaft supported in suitable bearings for adjusting said bar; a back strip adapted to telescope into the 125 chambers in said covers; one end of which is secured to said cross-bar and the other to the opposite cover, all coacting for the purpose specified.

3. The combination of the covers consist-

ing of rectangular frames; inner walls of sheet metal having inwardly and rearwardly turned flanges thereon embracing the sides of said frames; hinge projections on said flanges at their inner ends; rear walls for said covers secured to said flanges, thereby forming chambers in the said covers; clamping bars having holes therethrough, pivoted on said hinge projections; a curved block arranged in the chamber in one of said covers; a binding cord looped about said block and arranged through said clamping bars, and projecting into the chamber in the opposite cover; a cross-bar to which the ends of said binding cord are secured; a threaded shaft supported in suitable bearings for adjusting said bar; a back strip adapted to telescope into the chambers in said covers; and elastic tapes for connecting one end of said back strip to said cross-bar and the other end to the opposite cover, all coacting for the purpose specified.

4. The combination of the covers consisting of rectangular frames; inner walls of sheet metal having rearwardly and inwardly turned flanges thereon embracing the sides of said frames; hinge projections on said flanges at their inner ends; rear walls for said covers secured to said flanges thereby forming chambers in the said covers; clamping bars having holes therethrough, pivoted on said hinge projections; a curved block arranged in the chamber in one of said covers; a binding cord looped about said block and arranged through said clamping bars, and projecting into the chamber in the opposite cover; a cross-bar to which the ends of said binding cord are secured; a threaded shaft supported in suitable bearings for adjusting said bar; a back strip adapted to telescope into the chambers in said covers, one end of which is secured to said cross-bar and the other to the opposite cover, all coacting for the purpose specified.

5. The combination of the covers consisting of rectangular frames; inner walls of sheet metal having rearwardly and inwardly turned flanges thereon embracing the sides of said frame; hinge projections on said flanges at their inner ends; rear walls for said covers secured to said flanges, thereby forming chambers in the said covers; clamping bars having holes therethrough, pivoted on said hinge projections; a curved block arranged in the chamber in one of said covers; a binding cord looped about said block and arranged through said clamping bars, and projecting into the chamber in the opposite cover; a cross-bar to which the ends of said binding cord are secured; means for adjusting said cross-bar; a back strip adapted to telescope into the chambers in said covers; and elastic tapes for connecting one end of said back strip to said cross-bar and the other end to the opposite cover, all coacting for the purpose specified.

6. The combination of the covers consisting of rectangular frames; inner walls of sheet metal having rearwardly and inwardly turned flanges thereon embracing the sides of said frames; hinge projections on said flanges at their inner ends; rear walls for said covers secured to said flanges, thereby forming chambers in the said covers; clamping bars having holes therethrough terminating in slot-like cavities at the rear, pivoted on said hinge projections; a curved block arranged in the chamber in one of said covers; a binding cord looped about said block and arranged through said clamping bars, and projecting into the chamber in the opposite cover; a cross-bar to which the ends of said binding cord are secured; means for adjusting said cross-bar; a back strip adapted to telescope into the chambers in said covers; one end of which is secured to said cross-bar and the other end to the opposite cover, all coacting for the purpose specified.

7. The combination of the covers consisting of rectangular frames; inner walls of sheet metal having rearwardly and inwardly turned flanges thereon embracing the sides of said frames; hinge projections on said flanges at their inner ends; rear walls for said covers secured to said flanges, thereby forming chambers in the said covers; clamping bars having holes therethrough, pivoted on said hinge projections; a curved block arranged in the chamber in one of said covers; a binding cord looped about said block and arranged through said clamping bars, and projecting into the chamber in the opposite cover; a cross-bar to which the ends of said binding cord are secured; means for adjusting said cross-bar; a back strip adapted to telescope into the chambers in said covers; and elastic tapes for connecting one end of said back strip to said cross-bar and the other end to the opposite cover, all coacting for the purpose specified.

8. The combination of the covers consisting of rectangular frames; inner walls of sheet metal having rearwardly and inwardly turned flanges thereon embracing the sides of said frames; hinge projections on said flanges at their inner ends; rear walls for said covers secured to said flanges thereby forming chambers in the said covers; clamping bars having holes therethrough, pivoted on said hinge projections; a curved block arranged in the chamber in one of said covers; a binding cord looped about said block and arranged through said clamping bars, and projecting into the chamber in the opposite cover; a cross-bar to which the ends of said binding cord are secured; means for adjusting said cross-bar; a back strip adapted to telescope into the chambers in said covers, one end of which is secured to said cross-bar and the other to the opposite cover, all coacting for the purpose specified.

9. The combination of the covers consisting of rectangular frames; inner walls of sheet metal having rearwardly and inwardly turned flanges thereon embracing the sides of said frames; hinge projections on said flanges at their inner ends; rear walls for said covers secured to said flanges, thereby forming chambers in the said covers; clamping bars having holes therethrough terminating in slot-like cavities at the rear, pivoted on said hinge projections; a curved block arranged in the chamber in one of said covers; a binding cord looped about said block and arranged through said clamping bars, and projecting into the chamber in the opposite cover; a cross-bar to which the ends of said binding cord are secured; and a threaded shaft supported in suitable bearings for adjusting said bar, all coacting for the purpose specified. 70
10. The combination of the covers consisting of rectangular frames; inner walls of sheet metal having rearwardly and inwardly turned flanges thereon embracing the sides of said frames; hinge projections on said flanges at their inner ends; rear walls for said covers secured to said flanges, thereby forming chambers in said covers; clamping bars having holes therethrough, pivoted on said hinge projections; a curved block arranged in the chamber in one of said covers; a binding cord looped about said block and arranged through said clamping bars, and projecting into the chamber in the opposite cover; a cross-bar to which the ends of said binding cord are secured; and a threaded shaft supported in suitable bearings for adjusting said bar; a back strip adapted to telescope into the chambers in said covers; and elastic connections for one end of said back strip to said cross-bar and the other end to the opposite cover, for the purpose specified. 75
11. The combination of the covers consisting of rectangular frames; inner walls of sheet metal having rearwardly and inwardly turned flanges thereon embracing the sides of said frame; hinge projections on said flanges at their inner ends; rear walls for said covers secured to said flanges, thereby forming chambers in said covers; clamping bars having holes therethrough, pivoted on said hinge projections; a curved block arranged in the chamber in one of said covers; a binding cord looped about said block and arranged through said clamping bars, and projecting into the chamber in the opposite cover; a cross-bar to which the ends of said binding cord are secured; and means for adjusting said cross-bar, all coacting for the purpose specified. 80
12. The combination of the covers consisting of rectangular frames; inner walls of sheet metal having rearwardly and inwardly turned flanges thereon embracing the sides of said frames; hinge projections on said flanges at their inner ends; rear walls for said covers secured to said flanges, thereby forming chambers in the said covers; clamping bars having holes therethrough, pivoted on said hinge projections; a curved block arranged in the 85
- chamber in one of said covers; a binding cord looped about said block and arranged through said clamping bars, and projecting into the chamber in the opposite cover; a cross-bar to which the ends of said binding cord are secured; and a threaded shaft supported in suitable bearings for adjusting said bar, all coacting for the purpose specified. 90
13. The combination of the covers consisting of rectangular frames; inner walls of sheet metal having rearwardly and inwardly turned flanges thereon embracing the sides of said frames; hinge projections on said flanges at their inner ends; rear walls for said covers secured to said flanges, thereby forming chambers in said covers; clamping bars pivoted on said hinge projections; binding cords secured to one of said covers and projecting into the opposite cover; a cross-bar to which the ends of said binding cord are secured; a threaded shaft supported in suitable bearings for adjusting said bar; a back strip adapted to telescope into the chambers in said covers; and elastic connections for one end of said back strip to said cross-bar and the other end to the opposite cover, for the purpose specified. 95
14. The combination of the covers consisting of rectangular frames; inner walls of sheet metal having rearwardly and inwardly turned flanges thereon embracing the sides of said frames; hinge projections on said flanges at their inner ends; rear walls for said covers secured to said flanges, thereby forming chambers in said covers; clamping bars pivoted on said hinge projections; binding cords secured to one of said covers and projecting into the opposite cover; a cross-bar to which the ends of said binding cord are secured; a threaded shaft supported in suitable bearings for adjusting said bar; a back strip adapted to telescope into the chambers in said covers; and elastic connections for one end of said back strip to said cross-bar and the other end to the opposite cover, for the purpose specified. 100
15. The combination of the covers consisting of rectangular frames; inner walls of sheet metal having rearwardly and inwardly turned flanges thereon embracing the sides of said frames; hinge projections on said flanges at their inner ends; rear walls for said covers secured to said flanges, thereby forming chambers in said covers; clamping bars pivoted on said hinge projections; binding cords secured to one of said covers and projecting into the opposite cover; a cross-bar to which the ends of said binding cord are secured; and a threaded shaft supported in suitable bearings for adjusting said bar, for the purpose specified. 110
16. The combination of the covers consisting of rectangular frames; inner walls of sheet metal having rearwardly and inwardly turned flanges thereon embracing the sides of said frames; hinge projections on said flanges at their inner ends; rear walls 115
- 120
- 125
- 130

- for said covers secured to said flanges, thereby forming chambers in said covers; clamping bars pivoted on said hinge projections; binding cords secured to one of said covers 5 and projecting into the opposite cover; adjusting means for said binding cords; a back strip adapted to telescope into the chambers in said covers; and elastic connections for one end of said back strip to said cross-bar 10 and the other end to the opposite cover, for the purpose specified.
17. The combination of the covers consisting of rectangular frames; inner walls of sheet metal having rearwardly and inwardly turned flanges thereon embracing the sides of said frames; hinge projections on said flanges at their inner ends; rear walls for said covers secured to said flanges, thereby forming chambers in said covers; clamping bars pivoted on said hinge projections; binding cords secured to one of said covers and projecting into the opposite cover; adjusting means for said binding cords; a back strip adapted to telescope into the chambers 20 in said covers, connected to said cross-bar, for the purpose specified.
18. The combination of the covers consisting of rectangular frames; inner walls of sheet metal having rearwardly and inwardly turned flanges thereon embracing the sides of said frames; hinge projections on said flanges at their inner ends; rear walls for said covers secured to said flanges; thereby forming chambers in said covers; clamping 30 bars pivoted on said hinge projections; binding cords secured to one of said covers and projecting into the opposite cover; and adjusting means for said binding cords, for the purpose specified.
19. The combination of covers having chambers or cavities therein; clamping bars having holes therethrough terminating in slot-like cavities at the rear, pivotally secured to said covers; a curved block arranged in the chamber in one of said covers; a binding cord looped about said block and arranged through said clamping bars; a cross-bar arranged in the opposite cover to which the ends of said binding cord are secured; a screw-threaded shaft supported in suitable bearings for adjusting said bar; a back strip adapted to telescope into the chambers in said covers; and yielding connections for said back strip to said cross-bar, for the purpose specified.
20. The combination of covers having chambers or cavities therein; clamping bars having holes therethrough terminating in slot-like cavities at the rear, pivotally secured to said covers; a curved block arranged in the chamber in one of said covers; a binding cord looped about said block and arranged through said clamping bars; a cross-bar arranged in the opposite cover to which the ends of said binding cord are secured; a screw-threaded shaft supported in suitable bearings for adjusting said bar, for the purpose specified.
21. The combination of covers having chambers or cavities therein; clamping bars pivotally secured to said covers; a curved block arranged in the chamber in one of said covers; a binding cord looped about said block and arranged through said clamping bars; a cross-bar arranged in the opposite cover to which the ends of said binding cord are secured; a screw-threaded shaft supported in suitable bearings for adjusting said bar; a back strip adapted to telescope into the chambers in said covers; and connections for said back strip to said cross-bar, for the purpose specified.
22. The combination of covers having chambers or cavities therein; clamping bars pivotally secured to said covers; a curved block arranged in the chamber in one of said covers; a binding cord looped about said block and arranged through said clamping bars; a cross-bar arranged in the opposite cover to which the ends of said binding cords are secured; a screw-threaded shaft supported in suitable bearings for adjusting said bar; a back strip adapted to telescope into the chambers in said covers; and connections for said back strip to said cross-bar, for the purpose specified.
23. The combination of covers having chambers or cavities therein; clamping bars having holes therethrough terminating in slot-like cavities at the rear, pivotally secured to said covers; a curved block arranged in the chamber in one of said covers; a binding cord looped about said block and arranged through said clamping bars; a cross-bar arranged in the opposite cover to which the ends of said binding cord are secured; and a screw-threaded shaft supported in suitable bearings for adjusting said bar, for the purpose specified.
24. The combination of covers having chambers or cavities therein; clamping bars pivotally secured to said covers; a curved block arranged in the chamber in one of said covers; a binding cord looped about said block and arranged through said clamping bars; a cross-bar arranged in the opposite cover to which the ends of said binding cord are secured; and a screw-threaded shaft supported in suitable bearings for adjusting said bar, for the purpose specified.
25. The combination of covers having chambers or cavities therein; clamping bars having holes therethrough, terminating in slot-like cavities at the rear, pivotally secured to said covers; a curved block arranged in the chamber in one of said covers; a binding cord wrapped about said block arranged

through said clamping bars and secured to the other one of said covers; means for adjusting said binding cord; a back strip adapted to telescope into the chambers in said cover; and yielding connections between said back strip and said cross bar, for the purpose specified.

26. The combination of covers having chambers or cavities therein; clamping bars having holes therethrough terminating in slot-like cavities at the rear, pivotally secured to said covers; a curved block arranged in the chamber in one of said covers; a binding cord wrapped about said block arranged through said clamping bars and secured to the other one of said covers; means for adjusting said binding cord; a back strip adapted to telescope into the chambers in said cover; and connections between said back strip and said cross bar, for the purpose specified.

27. The combination of covers having chambers or cavities therein; clamping bars, pivotally secured to said covers; a curved block arranged in the chamber in one of said covers; a binding cord wrapped about said block arranged through said clamping bars and secured to the other one of said covers; means for adjusting said binding cord; a back strip adapted to telescope into the chambers in said cover; and yielding connections between said back strip and said cross bar, for the purpose specified.

28. The combination of covers having chambers or cavities therein; clamping bars pivotally secured to said covers; a curved block arranged in the chamber in one of said covers; a binding cord wrapped about said block arranged through said clamping bars and secured to the other one of said covers; means for adjusting said binding cord; a back strip adapted to telescope into the chambers in said cover; and connections between said back strip and said cross bar, for the purpose specified.

29. The combination of covers having chambers or cavities therein; clamping bars having holes therethrough terminating in slot-like cavities at the rear, pivotally secured to said covers; a curved block arranged in the chamber in one of said covers; a binding cord wrapped about said block arranged through said clamping bars and secured to the other one of said covers; and means for adjusting said binding cord; for the purpose specified.

30. The combination of covers having chambers or cavities therein; clamping bars pivotally secured to said covers; a curved block arranged in the chamber in one of said covers; a binding cord wrapped about said block arranged through said clamping bars and secured to one of said covers; and means for adjusting said binding cord, for the purpose specified.

31. The combination of the covers having chambers or cavities therein; clamping bars having holes therethrough terminating in slot-like cavities at the rear, pivotally connected to said covers; binding cords arranged through said clamping bars and secured to one of said covers; means for adjusting said binding cords; a back strip adapted to telescope into the chambers in said covers; and yielding connections between said back strip and said adjusting means for said binding cords, for the purpose specified.

32. The combination of the covers having chambers or cavities therein; clamping bars having holes therethrough terminating in slot-like cavities at the rear, pivotally connected to said covers; binding cords arranged through said clamping bars and secured to one of said covers; means for adjusting said binding cords; a back strip adapted to telescope into the chambers in said covers; and connections between said back strip and said adjusting means for said binding cords, for the purpose specified.

33. The combination of the covers having chambers or cavities therein; clamping bars pivotally connected to said covers; binding cords arranged through said clamping bars and secured to one of said covers; means for adjusting said binding cords; a back strip adapted to telescope into the chambers in said covers; and yielding connections between said back strip and said adjusting means for said binding cords, for the purpose specified.

34. The combination of the covers having chambers or cavities therein; clamping bars pivotally connected to said covers; binding cords arranged through said clamping bars and secured to one of said covers; means for adjusting said binding cords; a back strip adapted to telescope into the chambers in said covers; and connections between said back strip and said adjusting means for said binding cords, for the purpose specified.

35. The combination of the covers; clamping bars having holes therethrough terminating in slot-like cavities at the rear, pivotally connected to said covers; binding cords arranged through said clamping bars and secured to one of said covers; means for adjusting said binding cords; a back strip and yielding connections between said back strip and said adjusting means for said binding cords, for the purpose specified.

36. The combination with the covers; clamping bars pivotally connected to said covers; binding cords arranged through said clamping bars secured to one of said covers, the openings in said clamping bars for said binding cords being of such size as to allow the clamping bars to rock thereon independently of the covers whereby the covers and the clamping bars may move independently in opening or closing the covers or the sheets clamped by said bars; and means for adjust-

- ing said binding cords carried by the opposite cover.
37. The combination of the covers having chambers or cavities therein; clamping bars 5 pivotally connected to said covers; binding cords secured to one of said covers; means carried by the opposite cover for adjusting said binding cords; a back strip adapted to telescope into the chambers in said covers; 10 and yielding connections between said back strip and said adjusting means for said binding cords, for the purpose specified.
38. The combination of the covers having chambers or cavities therein; clamping bars 15 pivotally connected to said covers; binding cords secured to one of said covers; means carried by the opposite cover for adjusting said binding cords; a back strip adapted to telescope into the chambers in said covers; 20 and connections between said back strip and said adjusting means for said binding cords, for the purpose specified.
39. The combination with the covers; clamping bars; binding cords secured to one 25 of said covers, arranged through said clamping bars, the openings in said clamping bars for said binding cord being of such size as to permit the rocking of the clamping bars thereon independently of the covers whereby 30 the covers and the clamping bars may move independently in opening or closing the covers or the sheets clamped by said bars; and means for adjusting said binding cords carried by the opposite cover.
- 35 40. The combination of the covers having chambers or cavities therein; clamping bars; 35 binding cords secured to one of said covers arranged through said clamping bars; means carried by the opposite cover for adjusting 40 said binding cords; a back strip adapted to telescope into the chambers in said covers; and yielding connections between said back strip and said adjusting means for said binding cords, for the purpose specified.
- 45 41. The combination of the covers having chambers or cavities therein; clamping bars; 45 binding cords secured to one of said covers, arranged through said clamping bars; means carried by the opposite cover for adjusting 50 said binding cords; a back strip adapted to telescope into the chambers in said covers; and connections between said back strip and said adjusting means for said binding cords, for the purpose specified.
- 55 42. The combination of the covers having chambers or cavities therein; clamping bars; 55 binding cords arranged through said clamping bars; means for adjusting said binding cords; a back strip adapted to telescope into the 60 chambers in said covers; and yielding connections between said back strip and said adjusting means for said binding cords, for the purpose specified.
43. The combination of the covers having chambers or cavities therein; clamping bars; 65 binding cords arranged through said clamping bar; means for adjusting said binding cords; a back strip adapted to telescope into the chambers in said covers; and connections between said back strip and said adjusting means for said binding cords, for the purpose specified.
44. The combination of the covers having chambers or cavities therein; clamping bars, 70 pivotally connected to said covers; binding cords; means for adjusting said binding cords; a back strip adapted to telescope into the chambers in said covers; and yielding connections between said back strip and said adjusting means for said binding cords, for the purpose specified.
45. The combination of the covers, having chambers or cavities therein; clamping bars, 75 pivotally connected to said covers; binding cords; means for adjusting said binding cords; a back strip adapted to telescope into the chambers in said covers; and connections between said back strip and said adjusting means for said binding cords, for the purpose specified.
46. The combination with the covers; clamping bars pivotally connected to said covers; binding cords arranged through said clamping bars, the openings in said clamping bars for said binding cords being of such size 85 as to permit the rocking of the clamping bars thereon independently of the covers whereby 90 the covers and the clamping bars may move independently in opening or closing the covers or the sheets clamped by said bars; and means for adjusting said binding cords carried by the opposite cover.
47. The combination of the covers; clamping bars pivotally connected to said covers; binding cords arranged through said clamping bars and secured to one of said covers; 95 the openings in said clamping bars for said binding cords being of such size as to permit the rocking of the clamping bars thereon and a screw for adjusting said binding cords carried by the opposite cover said binding cords being connected to said cover independently 100 of said clamping bars; for the purpose specified.
48. The combination with the covers; 105 clamping bars pivotally connected to said covers; binding cords secured to one of said covers; and a screw carried by the other cover for adjusting said binding cords, said binding cords being connected to said cover 110 and adjusting screw independently of said clamping bars.
49. The combination of the covers; clamping bars; binding cords secured to one of said covers arranged through said clamping bars, 115 the openings in said clamping bars for said binding cords being of such size as to permit the rocking of the clamping bars thereon;

- and a screw carried by the opposite cover for adjusting said binding cords said binding cords being connected to said cover independently of said clamping bars; as specified.
- 5 50. The combination of the covers; clamping bars; binding cords arranged through said clamping bars, the openings in said clamping bars for said binding cords being of such size as to permit the rocking of the 10 clamping bars thereon; and a screw arranged within one of said covers for adjusting said binding cords said binding cords being connected to said cover independently of said clamping bars; as specified.
- 15 51. The combination with the covers; clamping bars pivotally connected to said covers; binding cords secured to one of said covers; means carried by the other cover for adjusting the said binding cords, said binding cords being connected to said cover and to said adjusting means independently of said clamping bars.
- 20 52. The combination of the clamping bars; binding cords arranged through said clamping bars, the openings in said clamping bars for said binding cords being of such size as to permit the rocking of the clamping bars thereon; a screw for adjusting said binding cords; and covers pivotally connected to 25 clamping bars, one of said covers having a chamber therein in which said screw is arranged, said binding cords being connected 30 to said cover independently of said clamping bars; for the purpose specified.
53. The combination of the covers; clamp- 35 ing bars; binding cords arranged through said clamping bars, the openings in said clamping bars for said binding cords being of such size as to permit the rocking of the clamping bars thereon; and a screw carried 40 by one of said covers for adjusting said binding cords, said binding cords being connected to said cover independently of said clamping bars, for the purpose specified.
54. The combination with the covers; 45 clamping bars; a binding cord looped over a suitable bearing in one of said covers; a bar to which the ends of said binding cord are secured, arranged transversely in the chamber of the other cover; and means for adjusting 50 said bar.
55. The combination with the covers; a binding cord looped over a suitable bearing on one of said covers; a bar to which the ends of said binding cord are secured, arranged transversely of the other cover; and means for adjusting said bar.

In witness whereof I have hereunto set my hand and seal in the presence of two witnesses.

HARRY F. BUSHONG. [L. S.]
